(57) CLAIM

The ornamental design for a shoe, as shown and described.

DESCRIPTION

FIG. 1 is a front perspective view of a shoe showing my shoe design;

FIG. 2 is a rear perspective view of the shoe shown in FIG. 1;

FIG. 3 is a right side view of the shoe shown in FIG. 1;

FIG. 4 is a left side view of the shoe shown in FIG. 1;

FIG. 5 is a front view of the shoe shown in FIG. 1; and,

FIG. 6 is a rear view of the shoe shown in FIG. 1.

The broken line showing of the sole, heel, and portions of the upper is for illustrative purposes only and forms no part of the claimed design.
